UNITED STATES PATENT OFFICE.

WILLIAM VAN HORN, OF PIQUA, OHIO, ASSIGNOR OF ONE-HALF TO WALTER C. LENNOX, OF SAME PLACE.

FENCE.

SPECIFICATION forming part of Letters Patent No. 376,218, dated January 10, 1888.

Application filed November 20, 1886. Serial No. 219,503. (Model.)

To all whom it may concern:

Be it known that I, WILLIAM VAN HORN, a citizen of the United States, residing at Piqua, in the county of Miami and State of Ohio, have 5 invented certain new and useful Improvements in Fences; and I do hereby declare the following to be a full, clear, and exact description of the invention, such as will enable others skilled in the art to which it appertains to make and 10 use the same.

My invention relates to rail fences in which the several parts going to constitute the fence are bound together by wires.

The objects of my improvements are to provide 15 an easy method of reconstructing old rail fences that will save time, material, and space, and that will make a more substantial fence than methods heretofore used.

My improved rail fence consists, essentially, 20 of a series of rails, a rider-rail and forked stakes, a wire formed into two horizontal loops connected by a vertical loop, the upper horizontal loop embracing the upper portion of the forked stakes above the rider-rail and the 25 lower loop similarly embracing the forked stakes beneath the top rail of the fence, a tension-stake inserted within the central loop and turned vertically therein and against the adjacent stakes, and drawing the surplus wire 30 into the vertical loop, and a wire securing said tension stake in its vertical position, all as hereininafter set forth.

In the accompanying drawings, Figure 1 is 35 a perspective view of a panel of a fence constructed according to my improvements, and showing a tension-stake drawn from the lower fork. Fig. 2 is an end elevation of a section of a panel, showing the tension-stake drawn down from the upper fork. Fig. 3 is a side 40 elevation of a portion of a panel with the tension-stake drawn down from the upper fork. Fig. 4 represents an end perspective view of a portion of a fence-panel, showing in full lines the tension-stake in the upper fork and 45 in dotted lines the position said stake assumes when turned down. Fig. 5 represents a top plan view of one end of a fence-panel constructed according to my invention. Fig. 6 represents a detail view showing the course 50 of the binding-wire used to bind the cross-

stakes, the rider-rail, and the rail in the under fork together.

1 1 represent the cross or panel-bracing stakes, within the upper forks, 2, of which rests the upper longitudinal fork-retaining or rider 55 rail, 3, and 4 represents the lower longitudinal rail, placed within the lower forks, 5, said rails 3 4 serving, when secured in position, to maintain the forked character of the cross-rails and prevent their spreading apart either 60 at their upper or lower portions. 6 represents the tension-stake, and 7 represents the lower longitudinal rails. These parts constitute a panel of a fence as constructed according to 65 my present improvements.

8 represents the binder for securing the respective cross-stakes 1, tension-stake 6, and rails 3 and 4 together. This binder consists of a single length of wire, which, as represented in Fig. 6 of the drawings, is formed in 70 the act of securing said stakes and rails together into three loops—viz., a central vertical loop, 9, and top and bottom transverse loops, 10 11.

The manner of constructing a fence according to my present improvements is as follows: The stakes 1 are crossed together, as represented in the drawings, so as to form top and bottom forks, 2 and 5, respectively. The top or rider rail, 3, is then placed in position so 80 as to rest within the upper fork, 2, at each end of the panel, and thereby connect the respective forks and prevent the stakes from moving inward at their upper ends, and the lower rail, 4, is then placed within the lower 85 forks, 5, and the tension-stake 6 placed in a horizontal position, either within the lower forks and beneath the lower rail, 4, or else within the upper forks, 2, and above and upon the top or rider rail, 3. In either of 90 these stated positions of the tension-stake its tensile action upon the tie or wire binder will be the same, as will presently appear. The cross-stakes and the rails 3 4, connecting the same and preventing their spreading apart, 95 being thus placed in position, I take a suitable length of wire and pass it beneath the tension-stake 6, when such stake is placed in the lower fork, or when such stake is placed in the upper fork, then beneath the rail 4, and from 100

thence carry it around the cross-stakes 1, as represented, crossing the ends so as to form the loop 11, which acts as a support for the rail 4. From thence the ends of the binding-wire 8 are carried up to and over the top rail, 3, or where the tension-stake rests upon the top rail, as in Fig. 4, then over said stake, thus forming the central vertical loop, 9. The wire is then crossed and looped around the upper ends of the cross-stakes, as at 10, and its ends twisted together, as shown at 12. By thus forming the binder-wire it will be observed that the two horizontal top and bottom loops, 10 11, bind the cross-stakes and prevent their spreading, the lower loop, 11, also acting as a support for the rail 4, while the central loop, 9, serves to prevent sidewise movement of the rails 3 4, assists in supporting the rail 4, and also holds said rails 3 4 within their respective forks; and the top loop, 10, also operates to grip and bind the top rail in position. The binder 8, which is formed, as will be observed, from a single continuous piece of wire, having thus been placed in position, the tension-stake 6 is then turned down from its horizontal position, as represented in full lines, to a vertical position on one side of the rails, as represented in dotted lines at the left-hand side of Fig. 4 and in full lines in Figs. 2, 3, and 5; and as said tension-stake is thus drawn down it will, as represented in Figs. 2, 3, and 5, draw on the loop 10 of the binding-wire 8, and cause it to bind on the cross-stakes at the points *a a*, above the upper fork, and the points *b b*, below the under fork thereof. The same motion and the same operation will also cause the central loop, 9, of the wire to draw downward on the top rail, 3, and upward on the lower rail, 4, and tighten thereon, thereby holding said rails firmly in the upper and lower forks of the cross-stakes, which are held in position by the end loops.

The operation of the wire is this: it causes the cross-stakes to clamp the rails 3 and 4

firmly, and causes said rails to press tightly 45 into the upper and under forks of the cross-stakes, thus securing a reciprocal action of the rails and cross-stakes in the tightening process.

The rails 7 of each panel are secured to the tension-stake 6 by means of a wire, 14, which 50 is wrapped around said tension-stake above the rail 4 and brought down to the lower end of the tension-stake and secured to it beneath the bottom rail of the series. Said rails 7 and their securing-wire 14 are gripped to the tension-stake 6 by tie-wires 15, which are passed 55 around said tension stake and the wire 14, wrapped around and extending vertically thereof, as represented, so as to bind said wire tightly against the tension-stake; and as said wire 14 embraces the several rails 7, it necessarily follows that said rails 7 are thereby grippingly held against the respective tension-stakes. The tie-wires serve as stops to separate and prevent any possibility of the rails 7 60 moving out of position.

Having thus described my invention, what I claim is—

The herein-described rail fence, consisting of a series of rails, a rider-rail, and forked stakes, 70 a wire formed into two horizontal loops connected by a vertical loop, the upper horizontal loop embracing the upper portion of the forked stakes above the rider-rail and the lower loop similarly embracing the forked 75 stakes beneath the top rail of the fence, a tension-stake inserted within the central loop and turned vertically therein and against the adjacent stakes and drawing the surplus wire into the vertical loop, and a wire securing 80 said tension-stake in its vertical position, substantially as set forth.

In testimony whereof I affix my signature in presence of two witnesses.

WILLIAM VAN HORN.
